[57]**CLAIM**

The ornamental design for golf bag top, as shown and described.

DESCRIPTION

FIG. 1 is an isometric view showing my new design of the golf bag top of the invention;

FIG. 2 is a front view in elevation of the golf bag top of the invention, the right side, left side and rear views being identical thereto;

FIG. 3 is a top planar view thereof;

FIG. 4 is a bottom planar view thereof; and,

FIG. 5 is a cross-sectional view taken along line 5—5 of FIG. 2 and is shown for clarity.

The broken line showing of golf bag is for illustrative purpose only and forms no part of the design.
